UNITED STATES PATENT OFFICE

130,601

DESIGN FOR AN OTOSCOPE OR THE LIKE

William F. Peck, Snyder, Albin A. Gradisar,
Buffalo, and John T. Armbruster, Niagara Falls,
N. Y.

Application September 10, 1941, Serial No. 103,272

Term of patent 14 years

To all whom it may concern:

Be it known that we, (1) William F. Peck, (2) Albin A. Gradisar, and (3) John T. Armbruster, citizens of the United States, residing at (1) Snyder, (2) Buffalo, and (3) Niagara Falls, in the counties of (1) and (2) Erie, and (3) Niagara and State of New York, have invented a new, original and ornamental Design for an Otoscope or the like, of which the following is a specification, reference being made to the accompanying drawing, forming a part thereof.

Fig. I is a side elevational view of an otoscope or the like embodying our new design; and

Fig. II is a top plan view of the otoscope or the like shown in Fig. I.

The characteristic features of the design reside in the portions shown in full lines in the drawing.

What is claimed is:

The ornamental design for an otoscope or the like, substantially as shown and described.

WILLIAM F. PECK.
ALBIN A. GRADISAR.
JOHN T. ARMBRUSTER.
